UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

965,423.

Specification of Letters Patent. Patented July 26, 1910.

Application filed October 24, 1907. Serial No. 399,045.

To all whom it may concern:

Be it known that I, JESSE G. VINCENT, a citizen of the United States, residing at Detroit, in the county of Wayne and State of Michigan, have invented certain new and useful Improvements in Adding-Machines, of which the following is a specification.

The object of the present invention is to provide improved means in an adding machine for automatically characterizing totals and sub-totals, as distinguished from other amounts printed in a list, designating numbers as distinguished from added amounts, and the first amount in a list of added amounts, as distinguished from subsequent amounts in the same list. It will be understood that means for carrying out this object will be embodied in an adding machine equipped for printing lists of amounts and accumulating the total thereof and printing such total with or without leaving the machine clear and also equipped for printing a number while excluding it from the accumulation.

In the present instance the invention is shown and described as embodied in a well known type of adding machine, to-wit, the Burroughs machine of the general character disclosed in Patents Nos. 504,963 and 505,078, issued September 12, 1893, but it is to be understood that the invention is not restricted to employment in connection with this particular type of adding machine, but may be adapted to other types.

In the accompanying drawings which form part of this specification, Figure 1 represents in left side elevation a sufficient portion of the interior mechanism of a Burroughs adding machine to illustrate the application of the present invention thereto, the parts being here shown in what may be termed normal condition, *i. e.*, the condition in which they are left after a clearing operation; Fig. 2 represents in left side elevation certain parts employed to carry out the present invention, these parts being shown in the relative positions assumed when the machine is in the middle of an operation to start an accumulation by putting an amount into the accumulator and printing it at the head of a list; Fig. 3 is a similar view illustrating the changed relation of the parts when such operation has been completed and the machine is to be operated to accumulate a second amount; Fig. 4 is a

view similar to Fig. 2 with additional parts, this view illustrating relative positioning when the machine is in the middle of an operation in which a designating number is printed without accumulation, dotted lines 60 illustrating normal positions of certain parts; Fig. 5 is a right hand continuation of Fig. 4, duplicating some of the parts illustrated in the latter; Fig. 6 is a view similar to the right hand portion of Fig. 1, on the same scale but illustrating a changed relation of parts which occurs when a total is to be printed and the machine cleared; and Fig. 7 is a somewhat similar view illustrating the effect of depressing a key which causes a total to be printed but the accumulation to be preserved; to wit the so-called subtotal.

Referring first to Fig. 1 of the above described drawings, the numeral 600 designates a rock shaft located about centrally of the machine and upon which a series of levers 611 are loosely mounted, said levers carrying at their forward ends segmental racks 610 and at their rear ends segmental series of type plates 618, as in the usual Burroughs machine. Reference numeral 900 designates another rock shaft at the lower front part of the machine, this rock shaft having secured to it the frame in which the adding or accumulating wheels are mounted. Reference numeral 910 designates one side plate of said frame and 916 designates one of the pinions which constitute accumulating wheels ordinarily carrying numbered disks for indicating purposes. The reference numeral 613 designates a frame or bail secured to the rock shaft 600 and normally upholding the forward arms of the levers 611 but retreating in every operation of the machine so as to permit said levers to fall. Latches 415 normally engage the racks 610 to uphold them, but are severally displaced by depression of amount keys and collectively displaced by depression of total or sub-total keys. The amount keys are designated 291 and arranged as usual in parallel rows, the keys of each row coöperating with a sliding strip 214 engaged with one of the latches 415. The pinions 916 are normally engaged with the racks 610 but at the outset of an operation of the machine when an amount is to be accumulated said pinions are moved out of mesh with said racks. The latter 110

descend distances determined by stops which the depressed amount keys project into the paths of shoulders on the racks. Thereafter the pinions return to engagement with the racks so as to be turned thereby when the racks are restored to normal by the frame 613. When the forward arms of the levers 611 drop the rearward arms of these levers of course rise and thus the amount represented by the depressed keys is set up in type confronting a roller platen 17.

When a total is to be printed, the pinions 916 remain in mesh with the racks 610 so that the descent of the latter will be limited by the zero stops for said pinions. If the machine is to be left clear, *i. e.*, the pinions to remain at zero position, then they will be disengaged from the racks 610 before the latter start upward. If, on the other hand, the accumulation is to be preserved the pinions are kept in mesh with the racks during the restoration of the latter to normal. The engagement between pinions and racks is controlled by the rocking of the frame in which the pinions are mounted and the rocking of this frame is effected through the medium of the familiar pitman 914 branched at its forward end to alternately engage studs *a* and *b* on the plate 910 above and below the rock shaft 900. The upper branch of the pitman is notched to engage the stud *a* and through this engagement the accumulator is controlled in an adding operation. The lower branch of the pitman is hooked to engage the stud *b*, but normally stands a short distance above the same. The pitman is reciprocated as usual through the medium of a three-armed lever 913, the middle depending arm of which is jointed to the pitman and the forwardly and rearwardly extending arms of which carry studs *c* and *d*. The usual rock arm 813 is employed, the same being secured to a rock shaft 800 which is oscillated in every operation of the machine. This rock arm carries the usual wipe plate or pawl 821 coöperating with the studs *c* and *d*. The forward end of the pitman is normally upheld as usual through the medium of a link 911 slotted at its upper end to embrace a screw stud *e* on a bell crank lever 227 pivoted just under the keyboard and drawn forward by a comparatively strong spring *f*. An upstanding arm of said bell crank 227 is surmounted by a key button 293 which is ordinarily termed the total key. The depression of this key against the stress of the spring *f* permits the forward end of the pitman 914 to drop so that the hook of the pitman comes to rest upon the stud *b*, (Fig. 6) the screw stud *e* then moving to the lower end of the slot of the link 911. Of course, this lowering of the pitman breaks the connection between it and the accumulating frame above the rock shaft 900,

so that the forward thrust of the pitman does not effect disengagement of the pinions and racks. The result of this forward thrust of the pitman is to carry the hook of the pitman off the top of the stud *b*, (dotted lines Fig. 6) whereupon said hook drops over the front side of the stud. Then, when the pitman moves rearwardly the accumulator frame is rocked to disengage the pinions from the racks. This is the ordinary totaling operation in a Burroughs adding machine. It is customary in such machine when a so called sub-total is desired, to release the key 293 in the middle of an operation of the machine so as to cause the hook of the pitman to be lifted above the stud *b* prior to the rearward movement of the pitman, thus preventing the pinions from being moved out of engagement with the racks. In the construction here shown and described the so called sub-total is not taken in this way, but an additional key is employed, the depression of which causes depression of the key 293, but prevents the drop of the pitman 914 otherwise permitted by the slot in link 911.

Referring to the sub-total means just mentioned the reference letter *S* designates a key in rear of the key 293 and surmounting an upstanding arm of a bell crank lever *S*¹ loosely mounted on the rock shaft 202 and connected with a forwardly extending link *S*² having a lug *s* which engages the front side of a stud *s*¹ on the depending arm of the bell crank 227. It will be seen that through the action of this lug *s* on the stud *s*¹ depression of the key *S* will result in depression of the key 293. In order to prevent the independent downward movement of the link 911 and the pitman 914, the link *S*² is extended past said link 911 and formed with a raised portion *s*² adapted when the link *S*² is drawn rearwardly to take up a position below a stud *s*³ on said link 911, thus blocking the descent of the latter, as illustrated in Fig. 7.

It is desirable to lock the sub-total key against depression when the total key has been operated and therefore means are provided for preventing rearward movement of the link *S*², so long as the total key is depressed. To this end, the link *S*² is formed with an angular or L-shaped slot *s*⁴ forwardly beyond the shoulder *s*², which slot embraces a fixed stud *s*⁵ on the framework of the machine. The link *S*² is normally upheld by a stud *s*⁶ on the link 911, (Fig. 1) so that the horizontal portion of the slot *s*⁴ is in line with the stud *s*⁵. A spiral spring *s*⁷ is preferably employed to draw downwardly upon the forward end of the link *S*², so that when the total key 293 is directly depressed the vertical branch of the slot *s*⁴ will be carried down over the stud *s*⁵ (Fig. 6) and the link *S*² thus locked against rear-

ward movement and the sub-total key consequently locked against depression. It is true that the total key is depressed by depression of the sub-total key, but the timing of movements of parts is such that the upper wall of the horizontal branch of the slot s^4 will have moved over the stud s^5 before the link S^2 is free to lower. This can be provided for by allowing lost motion between the lug s and the stud s^1 .

It will be seen that the above described construction provides for the performance by the machine of addition, at the same time printing the several amounts added, also the printing of the total of such amounts while restoring or preserving the accumulation, also the printing of such total, leaving the machine clear, *i. e.*, the printing of a subtotal, the latter without requiring manipulation of any key at an intermediate stage in an operation of the machine.

In the uses to which the present-day adding machine is put occasion frequently arises for printing a number, not an amount to be added, but merely a designating number, such for example as one indicating the identity of the particular person operating the machine. In a machine having the construction described the exclusion of such number from the accumulation may be accomplished by preventing effective engagement of the wipe plate or pawl 821 with the rear stud d of the lever 913. It will be recalled that in an adding operation the accumulator pinions 916 are disengaged from the racks 610 before the latter move downward. This is effected through the action of said wipe pawl upon the forward stud c . It is obvious that if said wipe pawl fails to act upon the rear stud d the pinions will remain disengaged from the racks during the return of the latter to normal. For the purpose of disabling said wipe pawl in this connection, a key E (Fig. 4) is located at the top of the keyboard, said key having a stem E^1 sliding through the top plates of the machine and guided at its lower end by a stud y which engages a slot in said stem. The lower extremity of the latter is rounded off on the front side and when the key is depressed the rounded edge stands in the path of the wipe pawl 821, so that as the rock arm 813 nears the end of its rearward swing, said wipe pawl will encounter said curved edge and be deflected, as illustrated in Fig. 5. The result is that when the rock arm swings forward the wipe pawl passes below the stud d without acting upon the same. The key E is normally elevated by a spring e^7 and when depressed is temporarily detained against the stress of said spring by a detent pawl e^1 pivoted below the upper part of the keyboard and pressed against the key stem by a spring e^2 , Fig. 4, so as to engage a notch e^3 , in said stem when the

latter reaches its lowest position. Said detent has a rearwardly projecting arm e^4 with an upturned extremity for co-action with the cross rod 200 of the usual key-releasing bail. The left side arm 219 of the latter is, as usual, connected by a link 226, with the depending arm of the total key bell crank lever 227, so that depression of either the total or sub-total key will release any depressed amount keys and will also release the key E , should that happen to have been depressed. The usual means will be employed for automatically operating said bail at the close of an operation of the machine.

In order to lock key E , which is ordinarily termed the elimination key, during the operation of the machine either in depressed or elevated position there is jointed to one side bar of the restoring frame 613, Fig. 5, a lock plate E^2 guided in its movements by a cross rod E^3 which occupies a bifurcation of said plate. The latter is formed on its front side with a flaring notch or opening e^6 adapted when the elimination key is depressed to embrace a lug e^6 on the inner side of the key stem E^1 , as illustrated in dotted lines, Fig. 5. When the key stem is elevated the said plate passes below the lug and prevents depression of the key during an operation of the machine. Normally, the plate E^2 , of course, stands in rear of said lug e^6 so as not to obstruct the key stem (Fig. 1).

Passing to the mechanism employed for effecting the printing, the type plates 618 are as usual mounted to have a slight sliding movement upon the levers 611 and the usual hammers 715 are employed to strike the rear ends of the type plates and drive them with percussive force against the paper overlying the platen 17. These hammers are as usual pivoted at their lower ends and formed with cam slots engaged by roller studs on levers 716, the latter connected by springs 780 with pawls 718. These springs constitute the means for effecting the percussive stroke of the hammers and they also serve to enforce engagement between said pawls and the series of pivoted latches 717 which normally engage the upper ends of the levers 716 to restrain them. The pawls 718 are as usual carried by a bail which swings back and forth in every operation of the machine and these pawls are formed with upturned tails co-acting with inclined shoulders of the levers 611, whereby any pawl in the train of mechanism controlled by a bank or row of keys in which none has been depressed will, with the forward swing of the bail, be thrown out of position for acting upon the latch. Notwithstanding this disablement, the latch may be displaced through co-operation with the next latch to the left, for the latches are provided with overlapping tails as usual, this being a familiar expedient for

securing the printing of ciphers in decimal places where no digits occur. The hammers are retracted by a bail 712 which is reciprocated in each operation of the machine in the 5 usual manner.

The printing of special characters for designating the totals, unadded numbers, and amounts heading added lists is effected through a train of impression mechanism 10 substantially duplicating that already described and located just to the right of those for acting on the type plates 618. For a purpose which will hereinafter become apparent, the special printing hammer is under 15 control of the other hammers, the right hand one of the latter which may be termed the units hammer, being formed with a notch g , Fig. 1, engaged by a pin or stud g^1 on the special printing hammer. It should also be 20 noted that the latch for restraining the special printing hammer is not overlapped by a tail of the adjacent or units latch.

The above mentioned special printing hammer acts upon one or the other of a pair 25 of special type plates F F^1 (Fig. 2) which are mounted to slide upon a carrier in the form of an arm F^2 loosely mounted on the shaft 600 alongside the units lever 611. The said arm F^2 is drawn upward by a spring h , 30 but is normally held depressed by reason of the engagement of a finger F^3 under a laterally turned end portion of an extension F^4 of said arm on the forward side of the shaft 600. Said finger F^3 is secured to this shaft, 35 which oscillates in each operation of the machine. Therefore, when the machine is operated the finger withdraws, leaving the arm F^2 free to rise in the absence of other obstructions. The plate F carries two type, 40 the upper one for designating the first amount of an added list and the lower one for designating an unadded number. The upper type may consist of the letter c and the lower type of the ordinary number sign, 45 $\#$, as indicated in several figures of the drawings. The type plate F^1 carries a single type for designating a total or sub-total, this type consisting, for example, of a star or asterisk. Normally, the type carrier 50 F^2 is in the lowered position illustrated in Fig. 3, where no one of the above described three type is in position to print.

The three different positions which the type carrier F^2 must assume in order to present its type at the printing line are determined by the coöperation between a specially formed portion of the upper edge of the carrier and an arm G which is secured to the rock shaft 202. This arm has a laterally projecting finger G^1 extending over the type carrier and the latter is irregularly notched for coöperation with said finger. Thus it is formed with a step i , a lower step 60 j somewhat more extensive than the step i , 65 then a notch k whose bottom is somewhat

lower than the step j and finally with a substantially V-shaped notch m of about the same depth as the notch k , but yet permitting greater movement of the type carrier, because further removed from the latter's pivot than the notch k . When the finger G^1 is positioned for engagement with said notch m (Fig. 6) the type carrier F^2 moves upward until the total type comes to the printing line. When said finger is in 70 position to engage the notch k (Fig. 4) the type carrier rises a less distance and the number sign type is brought to the printing line. When the finger is positioned for engagement with the step j (Fig. 2) the special type carrier rises only far enough to 75 present the "clear" type. The abutment of the shoulder i against said finger (Fig. 3) prevents the type carrier from leaving its non-printing position, when the finger 80 F^3 retreats.

Means for controlling the arm G will next be described. Near the left hand end of the rock shaft 202, there is secured upon it a bell crank lever H , the depending arm of 90 which is connected by a spring H^1 with a stud on an upstanding portion of the link 226, as shown in Fig. 1. Said spring thus tends to swing the bell crank H forward and consequently bring the arm G to its 95 foremost position engaging the high shoulder i , as shown in Fig. 3. The depending arm of the bell crank H carries a stud n , and an upstanding projection n^1 of the link 226 is located in front of said stud. Whenever 100 either the total or the sub-total key is depressed the resultant thrust of the link 226 rearward causes said upstanding projection n^1 to act upon said stud n and thereby swing the stop arm G to its extreme 105 rearward position, where its finger G^1 will be located for coöperation with the notch m , as illustrated in Fig. 6. Thus, when in an operation of the machine for taking a total the finger F^3 retreats the type-carrying arm will rise to the position where it presents at the printing line the type for 110 designating a total or sub-total.

The location of the stop finger G^1 for determining the number sign printing position of the special type carrier is brought about as follows: The depending arm of the bell crank H has on its inner side a roller stud O just in rear of the elimination key stem E^1 and the latter is formed with a 115 raised cam portion o^1 which, when the key is depressed acts upon said stud and thereby swings the bell crank and the stop arm G rearwardly, positioning the stop finger G^1 over the notch k , as shown in Fig. 4. 120

It will be understood that, after there has been a clearing operation of the machine, the stop finger G^1 should, in the next ensuing adding operation, be located over the shoulder j of the special type carrier. The 130

control of the stop arm, to this end, is brought about through the following described means. The forwardly extending arm of the bell crank H is formed with an upstanding portion p shouldered as at p¹ and extending through a slot p² in a sliding plate P and also through a slot p³ in the under top plate of the machine, as clearly shown in Fig. 4. When the two slots are out of register, the plate P being slid forward, the shoulder p¹ will strike against said plate and thus the stop finger G¹ will be located over the shoulder j (Fig. 1). The plate P is slid to its forward position in a clearing operation through the medium of a bell crank lever P², whose forward arm overlies the stud s³ on the link 911 (Fig. 6) and whose upwardly projecting arm extends in rear of a stud p⁴ on a downturned lip of the plate P. A comparatively strong spring p⁵ connects the said upstanding arm of the bell crank lever P² with a post p⁶ depending from the under top plate of the machine and when free to act, this spring serves to draw the plate P to its foremost position. The extent of movement of the bell crank lever P² in so acting is controlled by the stud s³ and unless the link 911 moves downward far enough for a clearing operation of the machine the bell crank P² cannot draw the plate P far enough forward to present an abutment to the shoulder p¹ of the bell crank lever H. Consequently the depression of the sub-total key will not have the effect of leaving the stop arm G in position to be abutted by the shoulder j of the special type carrier in the next ensuing adding operation.

When the two slots p² and p³ are in register then the shoulders p¹ may pass into the slot p², as shown in Figs. 2 and 3, permitting the stop arm G to swing to its foremost position where, as illustrated in Fig. 3, it prevents the special type carrier from leaving its non-printing position.

Now it will be understood that a clearing operation having resulted in drawing the apertured plate P forward and thereby presenting an abutment to the bell crank H which results in positioning the special type carrier to present its "clear" type at the printing line, the said type carrier must be held out of printing position during ensuing adding operations. To this end, means are provided for causing a rearward shift of the apertured plate P as an incident to an operation of the machine which prints the first of a list of added items or amounts, the slots p² and p³ being thus brought into alignment so that the stop finger G may move to position over the high step i of the type carrier arm F². The plate P is drawn rearwardly by a spring q connecting its rear end with a fixed post, though the spring p⁵ is necessarily superior to said spring q. However,

it will be understood that when the total key is elevated the bell crank lever P² is held away from the stud p⁴ of the slide plate P, the spring f being of course superior to the spring p⁵, and so said spring p⁵ is not then acting in opposition to the spring q. This condition is illustrated in Fig. 1. However, with the parts adjusted as there shown the plate is latched in its forward position. A downturned lip or flange r of the plate carries a stud r¹ which is engaged by the shoulder of a latch arm R pivoted just below the keyboard and drawn upward by a spring r² connecting a depending arm R¹ of the latch with a fixed post. The said depending arm R¹ of the latch carries a roller stud r³ arranged to act against a depending flange r⁴ of the plate P so that when the latch is disengaged from the stud r¹ it will act to thrust rearwardly the unlatched slide plate. It has been before stated that the spring q tends to draw said plate rearwardly, but the tension of said spring is not sufficient to overcome the friction between the shoulder p¹ of the bell crank H and the underside of the plate. When that friction has been eliminated through rearward movement of the plate by the latch arm R¹ then this spring q operates to move the plate farther back, thus insuring a free passage for the upstanding portion p of the bell crank H through the slot p².

It will be understood that the unlatching of the slide plate and the rearward movement of the latter is to take place in an adding operation of the machine first ensuing after a clearing operation, but of course the mere depression of amount keys should not bring about the release of the plate because that act may not be followed by an operation of the machine and furthermore the operation of the machine following depression of amount keys may be one in which a designating number is to be printed and no addition performed. For these reasons, depression of amount keys merely has the effect of moving a latch-operating member so that if the operation is an adding one this member will be acted upon so as to withdraw the latch from effective position. However, the depression of the elimination key will have such an effect upon the connections between this member and the amount keys as to prevent actuation of said member in the ensuing operation of the machine. The member in question takes the form of a pitman Q pivoted to the latch and carrying at its lower end a roller stud s designed to be acted upon by a finger u¹ secured to the rock shaft 600. The amount-key detent strips 214 coöperate as usual with a bail 424 moving the latter rearward whenever any amount key is depressed. The left hand side of this bail is connected by an irregular-shaped link Q¹ with the pitman Q and with the stem of the

elimination key E (Fig. 5). Said link Q¹ is formed at its rear end with a straight longitudinal slot u² embracing a stud u³ on said elimination key stem which mode of connection permits the necessary backward and forward thrust of said link. The latter in its oblique and widened middle portion is formed with an angular slot u⁴ embracing a stud u⁵ on the pitman Q. Normally as shown in Fig. 1, the said stud u⁵ is in the substantially vertical portion of said angular slot, though at the upper end of such portion of the slot. Consequently, when the bail 424 is swung rearwardly the pitman Q will be swung rearwardly through the medium of the link Q¹ and the stud u will be brought into the path of the finger u¹ on the shaft 600 (dotted lines Fig. 5). The result is that in the ensuing operation of the machine the said pitman will be drawn downwardly and the latch disengaged from the plate and the latter thrust rearwardly by the arm R¹ of the latch and disengaged from the shoulder p¹ of the bell crank H, whereupon the spring q will move the slide plate farther back. It will be remembered that in this operation of the machine the stop finger G¹ was at the outset positioned over the elongated step j of the type-carrier arm. Before the pitman Q is operated in the manner just described the type carrier arm will have swung upwardly and its said elongated step will have come in contact with the finger G¹. The "clear" special character will therefore be printed in association with the amount. It is the rear portion of the elongated step which then abuts the stop finger, as will be apparent from an inspection of Fig. 1. When the finger u¹ acts on the pitman Q and the slide plate is moved rearward said stop finger advances to the forward part of said elongated step, taking up the position shown in Fig. 2. Then when the special type carrier is carried down by the action of the finger F³ against the forward extension F⁴ of the type carrier, said stop finger will move to position above the high step i, as shown in Fig. 3, this being effected by the spring H¹. Therefore, as further amounts are added to the accumulation, there will be no special character-printing, as the special type carrier is held out of printing position.

When a designating number is to be printed without accumulation the above described operation should not take place because if it did then when the adding commenced the first amount would not be characterized to indicate "clear". Therefore, the depression of the elimination key prevents any co-action between the pitman Q and its operating finger u¹. Thus, depression of the elimination key lowers the link Q¹ to the full-line position shown in Fig. 5, thereby camming the pitman Q forward through co-

operation of the upper inclined portion of the angular slot u⁴ with the stud u⁵. Hence when amount keys are depressed and the link Q¹ thrust rearwardly the pitman stud u will not be brought into the path of the actuating finger u¹, and so the plate P will not be unlatched.

Of course, there should be no printing of special characters in blank operations of the machine and consequently the special printing hammer is only permitted to act when the adjacent units hammer acts. The interlock between these two hammers has before been mentioned as comprising a notch g and a stud g¹ shown in Fig. 1. It will, of course, be understood that in the printing of any item, whether representing an added amount, a total, or a designating number, the units hammer will necessarily operate and release the special printing hammer from the restraint of the described interlock. But in blank operations of the machine, even though the total, subtotal or elimination key be depressed, there will be no special character printing, the units-hammer being restrained by its latch and the special hammer by the units hammer. It has before been stated that there is no co-operative action between the units latch and the special latch such as exists between the regular latches for cipher printing purposes. If so, the special printing hammer would be constantly delivering blows with the special type carrier out of printing position. So far as individual actuation of the special latch by pawl 718 is concerned, that is prevented when the special type carrier is out of position, in the same manner that actuation of the regular latches is prevented. Thus the special pawl has an upturned tail 105 which co-acts with an inclined shoulder x on the underside of the type carrier arm. The above described construction is well adapted for carrying out the object primarily stated, but it is to be understood that said construction is susceptible of considerable modification without departing from the scope of the invention.

I claim:

1. In a machine of the character described, the combination with adding and listing mechanisms, and controlling devices therefor designed to effect a clearing operation, of a special type carrier for characterizing the first of a list of added amounts, said carrier normally withdrawn from printing position, a stop piece for limiting the advance of said type carrier, and means coming into play in the clearing operation to shift the stop piece and permit the type carrier to advance beyond the position for printing to characterize the first added amount, with provisions for limiting the return of said stop piece and thus positioning it to limit the advance of the type carrier in 130

an adding operation of the machine first ensuing after a clearing operation and thereby position the type carrier for characterizing the first of a list of added amounts.

- 5 2. In a machine of the character described, the combination with adding and listing mechanisms, and controlling devices therefor designed to effect a clearing operation, 10 of a special type carrier for characterizing the first of a list of added amounts, said carrier normally withdrawn from printing position, a stop piece for limiting the advance of said type carrier, means coming into play 15 in the clearing operation to shift the stop piece and permit the type carrier to advance beyond the position for printing to characterize the first added amount, with provisions for limiting the return of said stop 20 piece and thus positioning it to limit the advance of the type carrier in an adding operation of the machine first ensuing after a clearing operation and thereby position the type carrier for characterizing the first of a 25 list of added amounts, and means controlled by the adding mechanism for then freeing the stop piece and permitting it to return to normal for detaining the type carrier out of printing position.
- 30 3. In a machine of the character described, the combination with adding and listing mechanisms and controlling devices therefor designed to effect a clearing operation and the printing of a total, of a special type carrier normally withdrawn from printing position and having a type to characterize a total and a type to characterize the first of a list of added items or amounts, a stop piece for limiting the advance of the type carrier, 35 and means coming into play in the clearing and total printing operation to shift the stop piece and permit the type carrier to advance beyond a position for presenting at the printing line the first-item-characterizing type and to a position for presenting the total-characterizing type, with provisions for limiting the return of the stop piece and thus positioning it to limit the advance of the type carrier causing the latter 40 to present its first-item-characterizing type in an adding operation first ensuing after a clearing and total-printing operation.
- 45 4. In a machine of the character described, the combination with adding and listing mechanisms and controlling devices therefor designed to effect a clearing operation and the printing of a total, of a special type carrier normally withdrawn from printing position and having a type to characterize a 50 total and a type to characterize the first of a list of added items or amounts, a stop piece for limiting the advance of the type carrier, means coming into play in the clearing and total printing operation to shift the stop piece and permit the type carrier to advance beyond the position for printing to characterize the first added amount, with provisions for limiting the return of said stop piece and thus positioning it to limit the advance of the type carrier in an adding operation of the machine first ensuing after a clearing operation and thereby position 55

beyond a position for presenting at the printing line the first-item-characterizing type and to a position for presenting the total-characterizing type, with provisions for limiting the return of the stop piece and thus positioning it to limit the advance of the type carrier causing the latter to present its first-item-characterizing type in an adding operation first ensuing after a clearing and total-printing operation, and means controlled by the adding mechanism for then freeing the stop piece and permitting it to return to normal for detaining the type carrier out of printing position.

5 5. In a machine of the character described, the combination with adding and listing mechanisms and controlling devices therefor designed to effect a clearing operation and the printing of a total, with provisions for printing a total without clearing; of a special type carrier normally withdrawn from printing position and having a type to characterize a total and a type to characterize the first of a list of added items or amounts, a stop piece for limiting the advance of the type carrier, means coming into play in the clearing and total printing operation to shift the stop piece and permit the type carrier to advance beyond a position for presenting at the printing line the first-item-characterizing type and to a position for presenting the total-characterizing type, with provisions for limiting the return of the stop piece and thus positioning it to limit the advance of the type carrier causing the latter to present its first-item-characterizing type in an adding operation first ensuing after a clearing and total printing operation, and means controlled by the adding mechanism for then freeing the stop piece and permitting it to return to normal for detaining the type carrier out of printing position.

6. In a machine of the character described, the combination of adding and listing mechanisms with provisions for printing without adding; controlling connections designed to effect a clearing operation; a special type carrier normally withdrawn from printing position and having a type for characterizing an unadded number and a type for characterizing the first of a list of added amounts, a stop piece for limiting the advance of said type carrier, means coming into play in the clearing operation to shift the stop piece and permit the type carrier to advance beyond the position for printing to characterize the first added amount, with provisions for limiting the return of said stop piece and thus positioning it to limit the advance of the type carrier in an adding operation of the machine first ensuing after a clearing operation and thereby position

the type carrier for characterizing the first of a list of added amounts; and means coming into play in a non-adding operation to shift the stop piece and permit the type carrier to advance beyond the first-item-characterizing position to a position for presenting the type which characterizes an un-added item.

7. In a machine of the character described, 10 the combination of adding and listing mechanisms with provisions for printing without adding; controlling connections designed to effect a clearing operation; a special type carrier normally withdrawn from printing 15 position and having a type for characterizing an unadded number and a type for characterizing the first of a list of added amounts, a stop piece for limiting the advance of said type carrier, means coming 20 into play in the clearing operation to shift the stop piece and permit the type carrier to advance beyond the position for printing to characterize the first added amount, with provisions for limiting the return of said 25 stop piece and thus positioning it to limit the advance of the type carrier in an adding operation of the machine first ensuing after a clearing operation and thereby position the type carrier for characterizing the first 30 of a list of added amounts, means controlled by the adding mechanism for then freeing the stop piece and permitting it to return to normal for detaining the type carrier out of printing position, and means 35 coming into play in a non-adding operation to shift the stop piece and permit the type carrier to advance beyond the first-item-characterizing position to a position for presenting the type which characterizes an un-added item, with provisions for disabling the said stop-piece freeing means when a 40 number is printed without being added.

8. In a machine of the character described, 45 the combination of adding and listing mechanisms with provisions for printing without adding; controlling connections designed to effect a clearing and total printing operation; a special type-carrier normally withdrawn from printing position and having a 50 type for characterizing an unadded number, a type for characterizing a total and a type for characterizing the first of a list of added amounts; a stop piece for limiting the advance of said type carrier; means coming 55 into play in the clearing and total printing operation to shift the stop piece and permit the type carrier to advance beyond a position for presenting at the printing line the first-item-characterizing type and to a position 60 for presenting the total-characterizing type, with provisions for limiting the return of the stop piece and thus positioning it to limit the advance of the type carrier causing the latter to present its first-item-characterizing type in an adding operation first en-

suing after a clearing and total-printing operation, and means coming into play in a non-adding operation to shift the stop piece and permit the type carrier to advance beyond the first-item-characterizing position 70 to a position for presenting the type which characterizes an unadded item.

9. In a machine of the character described, 75 the combination of adding and listing mechanisms with provisions for printing without adding; controlling connections designed to effect a clearing and total printing operation; a special type-carrier normally withdrawn from printing position and having a type for characterizing an unadded number, 80 a type for characterizing a total and a type for characterizing the first of a list of added amounts; a stop piece for limiting the advance of said type carrier; means coming into play in the clearing and total printing 85 operation to shift the stop piece and permit the type carrier to advance beyond a position for presenting at the printing line the first-item-characterizing type and to a position for presenting the total-characterizing 90 type, with provisions for limiting the return of the stop piece and thus positioning it to limit the advance of the type carrier causing the latter to present its first-item-characterizing type in an adding operation first 95 ensuing after a clearing and total-printing operation, means controlled by the adding mechanism, for then freeing the stop piece and permitting it to return to normal for detaining the type carrier out of printing position, 100 with provisions for disabling the said stop-piece freeing means when a number is printed without being added, and means coming into play in a non-adding operation to shift the stop piece and permit the type carrier to advance beyond the first-item-characterizing position to a position for presenting the type which characterizes an un-added item.

10. In a machine of the character described, 110 the combination of adding and listing mechanisms with provisions for printing without adding; controlling connections designed to effect a clearing and total printing operation, with provisions for printing 115 a total without clearing; a special type-carrier normally withdrawn from printing position and having a type for characterizing an unadded number, a type for characterizing a total and a type for characterizing the 120 first of a list of added amounts; a stop piece for limiting the advance of said type carrier; means coming into play in the clearing and total printing operation to shift the stop piece and permit the type carrier to advance 125 beyond a position for presenting at the printing line the first-item-characterizing type and to a position for presenting the total-characterizing type, with provisions for limiting the return of the stop piece and 130

thus positioning it to limit the advance of the type carrier causing the latter to present its first-item-characterizing type in an adding operation first ensuing after a clearing and total-printing operation, means controlled by the adding mechanism, for then freeing the stop piece and permitting it to return to normal for detaining the type carrier out of printing position, with provisions

5 for preserving the latter adjustment in the printing of a total without clearing, and means coming into play in a non-adding operation to shift the stop piece and permit the type carrier to advance beyond the first-item-characterizing position to a position for presenting the type which characterizes an unadded item, with provisions for disabling the said stop-piece freeing means when a number is printed without being added.

10 11. In a machine of the character described, the combination of an accumulator; a pivoted support therefor; reciprocating accumulator-actuators and type carriers; a pitman designed to engage the accumulator support alternately on opposite sides of the latter pivot; a key normally holding the pitman engaged with said support on one side of the latter pivot, said key when operated permitting the disengagement of said pitman from said support in that side of the latter's pivot and in the subsequent operation of the machine permitting the engagement of said pitman with said support in the opposite side of the latter's pivot; a second key arranged to operate the first key to so disengage the pitman on the one side of the pivot of the accumulator support but adapted to prevent engagement of the pitman with said support on the opposite side

15 of the latter's pivot; a special type carrier normally out of printing position and having a type for characterizing the first of a list of added items; and means under control of said two keys for bringing said special type carrier to printing position.

20 12. In a machine of the character described, the combination of an accumulator; a pivoted support therefor; reciprocating accumulator-actuators and type carriers; a pitman designed to engage the accumulator support alternately on opposite sides of the latter's pivot; a key normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot; a second key arranged to operate the first key to so disengage the pitman on the one side of the pivot of the accumulator support but adapted to prevent engagement of the pitman with said support on the opposite side

25 of the latter's pivot; a special type-carrier normally out of printing position and having a type for characterizing a total and a type for characterizing the first of a list of added items; and means under control of said two keys for bringing said special type carrier to its different printing positions.

30 13. In a machine of the character described, the combination of an accumulator; a pivoted support therefor; reciprocating accumulator-actuators and type carriers; a pitman designed to engage the accumulator support alternately on opposite sides of the latter's pivot; a key normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot; a second key arranged to operate the first key to so disengage the pitman on the one side of the pivot of the accumulator support but adapted to prevent engagement of the pitman with said support on the opposite side of the latter's pivot; a special type-carrier normally out of printing position and having a type for characterizing a total and a type for characterizing the first of a list of added items; a stop piece to determine different printing positions of said special type carrier and movable by the said keys to position for permitting said special type carrier to present its total designating type; and means for adjusting said stop piece to determine the first-item printing position of the special type-carrier; said means under control of the before-mentioned pitman and effective only when the latter is permitted, through operation of the first-mentioned key, to engage the accumulator support on the side of its pivot opposite that where said pitman normally engages said support.

35 14. In a machine of the character described, the combination of an accumulator; a pivoted support therefor; reciprocating accumulator-actuators and type carriers; setting-up devices therefor; a pitman designed to engage the accumulator support alternately on opposite sides of the latter's pivot; a key normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot; a second key arranged to operate the first key to so disengage the pitman on the one side of the pivot of the accumulator support but adapted to prevent engagement of the pitman with said support on the opposite side of the latter's pivot; a second key arranged to operate the first key to so disengage the pitman on the one side of the pivot of the accumulator support but adapted to prevent engagement of the pit-

man with said support on the opposite side of the latter's pivot; a special type-carrier normally out of printing position and having a type for characterizing a total and a type for characterizing the first of a list of added items; means under control of said two keys for bringing said special type carrier to its different printing positions; and means under control of the setting-up devices for holding the special type carrier in normal non-printing position.

15. In a machine of the character described, the combination of an accumulator; a pivoted support therefor; reciprocating accumulator-actuators and type carriers; setting-up devices therefor; a pitman designed to engage the accumulator support alternately on opposite sides of the latter's pivot; a key normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot; a second key arranged to operate the first key to so disengage the pitman on the one side of the pivot of the accumulator support but adapted to prevent engagement of the pitman with said support on the opposite side of the latter's pivot; a special type-carrier normally out of printing position and having a type for characterizing the first of a list of added items; a stop piece to determine different printing positions of said special type carrier and movable by the said keys to position for permitting said special type carrier to present its total designating type; means for adjusting said stop piece to determine the first-item printing position of the special type-carrier, said means under control of the before-mentioned pitman and effective only when the latter is permitted, through operation of the first-mentioned key, to engage the accumulator support on the side of its pivot opposite that where 50 said pitman normally engages said support; and means under control of the setting-up devices for moving the stop-piece to position for holding the special type-carrier in normal non-printing position.

55. 16. In a machine of the character described, the combination of an accumulator; a pivoted support therefor; reciprocating accumulator-actuators and type-carriers; a pitman designed to engage the accumulator support alternately on opposite sides of the latter's pivot; a key and slotted connecting link normally holding the pitman engaged with said support on one side of the latter's pivot, said key when operated permitting 60 the disengagement of said pitman from said

support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type carrier normally out of printing position and having a type for characterizing the first of a list of added amounts; and means for determining the printing position of the special type carrier, said means comprising a slide adapted to present an indexing abutment, and a spring-drawn bell-crank, one arm of which acts 80 against said slide and the other arm of which engages the slotted link.

17. In a machine of the character described, the combination of an accumulator; a pivoted support therefor; reciprocating accumulator-actuators and type-carriers; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type carrier normally out of printing position and having a type for characterizing the first of a list of added amounts; a stop piece for determining the printing position of the special type-carrier; and means for controlling the stop piece comprising a slide adapted to present an abutment thereto and a spring-drawn bell-crank, one arm of which acts on the slide and the other arm of which engages the slotted link.

18. In a machine of the character described, the combination of an accumulator; a pivoted support therefor; reciprocating accumulator-actuators and type-carriers; setting-up devices; a pitman designed to engage the accumulator support alternately on opposite sides of the latter's pivot; a key and slotted connecting link normally holding the pitman engaged with said sup-

port on one side of the latter's pivot, said key when operated permitting the disengagement of said pitman from said support on that side of the latter's pivot and in the 5 subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite 15 side of the latter's pivot by obstructing the link; a special type carrier normally out of printing position and having a type for characterizing the first of a list of added amounts; a stop piece for determining 20 the printing position of the special type-carrier; means for controlling the stop piece comprising a slide adapted to present an abutment thereto and a spring-drawn bell-crank, one arm of which acts on the 25 slide and the other arm of which engages the slotted link; means for latching the slide in the position to which it is moved by said bell crank, and means controlled by the setting-up devices for unlatching said 30 slide.

19. In a machine of the character described, the combination of an accumulator; a pivoted support therefor; reciprocating accumulator-actuators and type-carriers; 35 setting-up devices; a pitman designed to engage the accumulator support alternately on opposite sides of the latter's pivot; a key and slotted connecting link normally holding the pitman engaged with said support on one side of the latter's pivot, said key when operated permitting the disengagement 40 of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type carrier normally out of printing position and having a type for characterizing the first of a list of added amounts; a stop piece for determining 45 the printing position of the special type-carrier; means for controlling the stop piece comprising a slide adapted to present an abutment thereto and a spring-drawn bell-crank, one arm of which acts on the slide and the other arm of which engages the slotted link; a bell-crank lever one arm of which constitutes a latch for said slide and the other arm of which is adapted to act 50 against the slide to move it to ineffective position, a pitman connected to the last-mentioned bell-crank lever, a reciprocating member to actuate said pitman, and means for controlling the latter by the setting-up devices.

55 21. In a machine of the character described, the combination of an accumulator; a pivoted support therefor; reciprocating accumulator-actuators and type-carriers; 55 setting-up devices; a pitman designed to engage the accumulator support alternately on opposite sides of the latter's pivot; a key and slotted connecting link normally holding the pitman engaged with said support on one side of the latter's pivot, said key when operated permitting the disengagement 60 of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so dis-

in the position to which it is moved by said bell crank, and means controlled by the setting-up devices for unlatching said slide and shifting it to ineffective position.

20. In a machine of the character described, the combination of an accumulator; a pivoted support therefor; reciprocating accumulator-actuators and type-carriers; setting-up devices; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type carrier normally out of printing position and having a type for characterizing the first of a list of added amounts; a stop piece for determining the printing position of the special type-carrier; means for controlling the stop piece comprising a slide adapted to present an abutment thereto and a spring-drawn bell-crank, one arm of which acts on the slide and the other arm of which engages the slotted link; a bell-crank lever one arm of which constitutes a latch for said slide and the other arm of which is adapted to act against the slide to move it to ineffective position, a pitman connected to the last-mentioned bell-crank lever, a reciprocating member to actuate said pitman, and means for controlling the latter by the setting-up devices.

65 21. In a machine of the character described, the combination of an accumulator; a pivoted support therefor; reciprocating accumulator-actuators and type-carriers; 115 setting-up devices; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so dis-

engage the pitman on the one side of the pivot of the accumulator support but adapted to prevent engagement of the pitman with said support on the opposite side of the latter's pivot by obstructing the link; a special type carrier normally out of printing position and having a type for characterizing the first of a list of added amounts; a stop piece for determining the printing position of the special type-carrier; means for controlling the stop pieces comprising a slide adapted to present an abutment thereto and a spring-drawn bell-crank, one arm of which acts on the slide and the other arm of which 5 engages the slotted link, a bell-crank lever one arm of which constitutes a latch for said slide and the other arm of which is adapted to act against the slide to move it to ineffective position, a pitman connected 10 to the last-mentioned bell-crank lever, a reciprocating member to actuate said pitman, and a link engaged with said pitman and controlled by the setting-up devices to move the pitman into and out of position to 15 be acted upon by the said reciprocating member.

22. In a machine of the character described, the combination of an accumulator; a pivoted support therefor; reciprocating 20 accumulator-actuators and type carriers; a pitman designed to engage the accumulator support alternately on opposite sides of the latter's pivot; a key and slotted connecting link normally holding the pitman engaged with 25 said support on one side of the latter's pivot, said key when operated permitting the disengagement of said pitman from said support on that side of the latter's pivot and in the subsequent operation of the machine permitting the engagement of said pitman with 30 said support on the opposite side of the latter's pivot through independent movement of the link the length of its slot; a second key arranged to operate the first key to so disengage the pitman on the one side of the 35 pivot of the accumulator support but adapted to prevent engagement of the pitman with said support on the opposite side of the latter's pivot by obstructing the link; a special type-carrier normally out of printing position and having a type for characterizing a 40 total and a type for characterizing the first of a list of added items; a stop piece to determine different printing positions of said special type-carrier and movable by said 45 keys to positions for permitting said special type-carrier to present its total designating type; means for adjusting said stop piece to determine the first-item printing position of the special type-carrier, said means comprising a slide adapted to present an indexing abutment, and a spring-drawn bell-crank, one arm of which acts against said slide and the other arm of which engages the slotted link; means for latching the slide in the position to which it is moved by said bell-crank, and means controlled by the setting-up devices for unlatching said slide.

45 24. In a machine of the character described, the combination of an accumulator; a pivoted support therefor; reciprocating accumulators-actuators and type-carriers; setting-up devices therefor; a pitman designed to engage the accumulator support alternately on opposite sides of the latter's pivot; a key and slotted connecting link normally holding the pitman engaged with said support on one side of the latter's pivot, said 50 key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the 55 pivot of the accumulator support but adapted to prevent engagement of the pitman with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said keys to positions for permitting said special type-carrier to present its total designating type; and means for adjusting said stop piece to determine the first-item 60 printing position of the special type-carrier, said means comprising a slide adapted to present an indexing abutment, and a spring-drawn bell-crank one arm of which acts against said slide and the other arm of which engages the slotted link.

23. In a machine of the character described, the combination of an accumulator; a pivoted support therefor; reciprocating accumulators-actuators and type-carriers; setting-up devices therefor; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with 70 said support on the opposite side of the latter's pivot through independent movement of the link the length of its slot; a second key arranged to operate the first key to so disengage the pitman on the one side of the 75 pivot of the accumulator support but adapted to prevent engagement of the pitman with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said 80 keys to positions for permitting said special type-carrier to present its total designating type; means for adjusting said stop piece to determine the first-item printing position of the special type-carrier, said means comprising a slide adapted to present an indexing abutment, and a spring-drawn bell-crank, one arm of which acts against said slide and the other arm of which engages the slotted link; means for latching the slide in the position to which it is moved by said bell-crank, and means controlled by the setting-up devices for unlatching said slide.

85 24. In a machine of the character described, the combination of an accumulator; a pivoted support therefor; reciprocating accumulators-actuators and type-carriers; setting-up devices therefor; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on 90 that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the 95 pivot of the accumulator support but adapted to prevent engagement of the pitman with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said keys to positions for permitting said special type-carrier to present its total designating type; and means for adjusting said stop piece to determine the first-item printing position of the special type-carrier, said means comprising a slide adapted to present an indexing abutment, and a spring-drawn bell-crank one arm of which acts against said slide and the other arm of which engages the slotted link; means for latching the slide in the position to which it is moved by said bell-crank, and means controlled by the setting-up devices for unlatching said slide.

- with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said keys to positions for permitting said special type-carrier to present its total designating type; means for adjusting said stop piece to determine the first-item printing position of the special type-carrier, said means comprising a slide adapted to 15 present an indexing abutment, and a spring-drawn bell-crank, one arm of which acts against said slide and the other arm of which engages the slotted link; means for latching the slide in the position to which it is moved by said bell-crank, and means controlled by the setting-up devices for unlatching said slide and shifting to ineffective position.
25. In a machine of the character described, the combination of an accumulator; a pivoted support therefor; reciprocating accumulator-actuators and type-carriers; setting-up devices therefor; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said keys to positions for permitting said special type-carrier to present its total designating type; means for adjusting said stop piece to determine the first-item printing position of the special type-carrier, said means comprising a slide adapted to present an indexing abutment, and a spring-drawn bell-crank, one arm of which acts against said slide and the other arm of which engages the slotted link; a bell-crank lever one arm of which constitutes a latch for said slide and the other arm of which is adapted to act against the slide to move it to ineffective position, a pitman connected to the last-mentioned bell-crank lever, a reciprocating member to actuate said pitman, and a link engaged with said pitman and controlled by the setting-up devices to move the pitman into and out of position to be acted upon by the said reciprocating member.
26. In a machine of the character described, the combination of an accumulator; a pivoted support therefor; reciprocating accumulator-actuators and type-carriers; setting-up devices therefor; a pitman designed to engage the accumulator support alternately on opposite sides of the latter's pivot; a key and slotted connecting link normally holding the pitman engaged with said support on one side of the latter's pivot, said key when operated permitting the disengagement of said pitman from said support on that side of the latter's pivot and in the subsequent operation of the machine permitting the engagement of said pitman with said support on the opposite side of the latter's pivot through independent movement of the link the length of its slot; a second key arranged to operate the first key to so disengage the pitman on the one side of the pivot of the accumulator support but adapted to prevent engagement of the pitman with said support on the opposite side of the latter's pivot by obstructing the link; a special type-carrier normally out of printing position and having a type for characterizing a total and a type for characterizing the first of a list of added items; a stop piece to determine different printing positions of said special type-carrier and movable by said keys to positions for permitting said special type-carrier to present its total designating type; means for adjusting said stop piece to determine the first-item printing position of the special type-carrier, said means comprising a slide adapted to present an indexing abutment, and a spring-drawn bell-crank, one arm of which acts against said slide and the other arm of which engages the slotted link, a bell-crank lever one arm of which constitutes a latch for said slide and the other arm of which is adapted to act against the slide to move it to ineffective position, a pitman connected to the last-mentioned bell-crank lever, a reciprocating member to actuate said pitman, and a link engaged with said pitman and controlled by the setting-up devices to move the pitman into and out of position to be acted upon by the said reciprocating member.
27. In a machine of the character described, the combination of amount keys, a universal bail operated thereby, a link connected to said bail, a pitman engaged with said link, a reciprocating member to actuate the pitman, a latch to which the latter is connected, an abutment slide held in effective position by said latch, adding and printing mechanisms under control of said keys,

a special type-carrier associated with the printing mechanism and designed to characterize the first of a list of added amounts, a stop piece coöperating with said type-carrier and said slide to hold the former in printing position when the slide is latched, and means for effecting a clearing operation and thereby moving the slide to effective position, the next ensuing adding operation unlatching the slide substantially as and for the purpose described.

28. In a machine of the character described, the combination of amount keys, a universal bail operated thereby, a link connected to said bail, a pitman engaged with said link, a reciprocating member to actuate the pitman, a latch to which the latter is connected, an abutment slide held in effective position by said latch and adapted to be moved out of effective position by a branch of said latch when the latter releases the slide, adding and printing mechanisms under control of said keys, a special type-carrier associated with the printing mechanism and designed to characterize the first of a list of added amounts, a stop-piece coöperating with said type-carrier and said slide to hold the former in printing position when the slide is latched, and means for effecting a clearing operation and thereby moving the slide to effective position, the next ensuing adding operation unlatching the slide; substantially as and for the purpose described.

29. In a machine of the character described, the combination of amount keys, a universal bail operated thereby, a cam-slotted link connected to said bail, a pitman engaged with the cam slot of said link, a reciprocating member to actuate the pitman, a latch to which the latter is connected, an abutment slide held in effective position by said latch, adding and printing mechanisms under control of said keys, a special type-carrier associated with the printing mechanism and designed to characterize the first of a list of added amounts, a stop-piece coöperating with said type-carrier and said slide to hold the former in printing position when the slide is latched, means for effecting a clearing operation and thereby moving the slide to effective position, the next ensuing adding operation unlatching the slide, and a special key arranged to disable the adding mechanism, said key connected with the cam-slotted link and shifting the same to displace the pitman and prevent unlatching of the abutment slide.

30. In a machine of the character described, the combination of amount keys, a universal bail operated thereby, a cam-slotted link connected to said bail, a pitman engaged with the cam slot of said link, a reciprocating member to actuate the pitman, a latch to which the latter is connected, an

abutment slide held in effective position by said latch, adding and printing mechanisms under control of said keys, a special type carrier associated with the printing mechanism and having a type to characterize the first of a list of added amounts and a type to characterize an unadded number, a stop piece coöperating with said type carrier and said slide to hold the former in printing position when the slide is latched, means for effecting a clearing operation and thereby moving the slide to effective position, the next ensuing adding operation unlatching the slide, and a special key arranged to disable the adding mechanism, said key connected with the cam-slotted link and shifting the same to displace the pitman and prevent unlatching of the abutment slide, and said key setting the stop-piece to cause the special type carrier to present its type for characterizing an unadded item.

31. In a machine of the character described, the combination with a rocking accumulator, a pitman shiftably engaged therewith, a lever connected with said pitman, an oscillating arm having a wipe pawl to act on said lever, reciprocating actuators for the accumulator having type carriers, amount keys for determining the movements of the latter, a special type carrier having a type to characterize the first of a list of added items and a type to characterize an unadded item, a stop arm for determining the position of said special type-carrier, a special key having a stem with a cam-portion to act on said stop-arm to position it for causing the type carrier to present its type characterizing an unadded item, said key-stem arranged to enter the path of the wipe-pawl to prevent engagement of the accumulator with the set actuators; means for adjusting the pitman to effect a clearing operation and moving the stop-arm beyond the position for causing the special type carrier to prevent the type characterizing an unadded item; an abutment slide for holding said arm in position for causing the special type carrier to present its type which characterizes the first of a list of added items; means for moving said slide to effective position in the before mentioned clearing operation; a latch which holds said slide in effective position, a pitman for displacing the latch, a universal bail actuated by the amount keys, a link connected to said bail and having a cam-slot engaging the last-mentioned pitman and a slot engaging the stem of said special key, and a reciprocating member for acting on said last-mentioned pitman when amount keys are operated without operation of said special key.

32. In a machine of the character described, the combination of vertically reciprocating racks, accumulator pinions normally in mesh therewith, a pivoted car-

- rier for said pinions having studs above and below its pivot, a vertically movable and horizontally reciprocating pitman having a branch notched for engagement with the 5 upper stud and normally embracing the same and an oppositely extending branch hooked for engagement with the lower stud but normally elevated above the same, said pitman tending to drop disengaging its 10 notched branch from the associated stud and bringing its hooked branch to rest upon the lower stud, a link connected at one end with said pitman, a normally upheld total key lever having a slot and pin connection 15 with said link and equipped for direct depression to cause lowering of the link and consequent disengagement of the notched branch thereof from the upper stud leaving the link and pitman free to drop further as 20 permitted by the slot and pin connection and effectively engage its hooked branch with the lower stud, a separate depressible subtotal key lever, and a bar connected therewith and engaging the said total key 25 lever to depress the same, said bar adapted to engage the link and prevent the slot-and-pin drop of the pitman and having an angular slot engaging a fixed stud, the bar being normally upheld by the link but lowered upon depression of the total key lever and interlocked with said fixed stud to prevent depression of the sub-total key lever. 33. In a machine of the character described, the combination of vertically reciprocating racks, accumulator pinions normally in mesh therewith, a pivoted carrier for said pinions having studs above and below its pivot, a vertically movable and horizontally reciprocating pitman having a 35 branch notched for engagement with the upper stud and normally embracing the same and an oppositely extending branch hooked for engagement with the lower stud but normally elevated above the same, said pitman tending to drop disengaging its 40 notched branch from the associated stud and bringing its hooked branch to rest upon the lower stud, a link connected at one end with said pitman and having a laterally projecting stud or pin, a normally upheld total key lever having a slot and pin connection with said link and equipped for direct depression to cause lowering of the link and consequent disengagement of the notched branch 45 thereof from the upper stud leaving the link and pitman free to drop further as permitted by the slot and pin connection and effectively engage its hooked branch with the lower stud, a separate depressible sub-total 50 key lever, and a shouldered bar connected therewith and engaging the said total key lever to depress the same, the link stud normally standing above and beyond the shoulder of the bar but adapted upon direct depression of the total key lever to pass down 55 along said shoulder and prevent movement of the bar whereas when the subtotal key lever is depressed the bar is drawn under said link stud to prevent the slot-and-pin drop of the pitman, and the said bar having 60 an angular slot engaging a fixed stud, the bar being normally upheld by the link but lowered upon depression of the total key lever and interlocked with said fixed stud to prevent depression of the sub-total key lever. 34. In a machine of the character described, the combination with accumulating and printing mechanism; of means for eliminating accumulation, and a lock for preventing operation of such means during operation of the accumulating mechanism. 35. In a machine of the character described, the combination with accumulating and printing mechanism; of means for 65 eliminating accumulation, and a lock for preventing operation of such means during operation of the accumulating mechanism, with provisions for holding said means set during operation of the printing mechanism 70 unaccompanied by operation of the accumulating mechanism. 36. In a machine of the character described, the combination of accumulating and printing mechanisms and actuating 75 means therefor; of a depressible key for disabling the accumulating mechanism, and a lock for preventing depression of such key during operation of the accumulating mechanism by the actuating means. 37. In a machine of the character described, the combination of accumulating and printing mechanisms and actuating 80 means therefor; of a depressible key for disabling the accumulating mechanism, and a lock for preventing depression of such key during operation of the accumulating mechanism by the actuating means with provisions for holding said key depressed during 85 an operation of the printing mechanism unaccompanied by an operation of the accumulating mechanism. 38. In a machine of the character described, the combination of accumulating and printing mechanisms and actuating 90 means therefor; of a depressible key for disabling the accumulating mechanism, a latch for holding said key depressed, and a lock for preventing depression of such key during 95 operation of the accumulating mechanism by the actuating means. 39. In a machine of the character described, the combination of accumulating and printing mechanisms and actuating 100 means therefor; of a depressible key for disabling the accumulating mechanism, a latch for holding said key depressed, and a lock for preventing depression of such key during 105 operation of the accumulating mechanism by the actuating means, with provisions for holding said key depressed during an operation of the printing mechanism unaccompanied by an operation of the accumulating mechanism. 40. In a machine of the character described, the combination of accumulating and printing mechanisms and actuating 110 means therefor; of a depressible key for disabling the accumulating mechanism, a latch for holding said key depressed, and a lock for preventing depression of such key during 115 operation of the accumulating mechanism by the actuating means. 41. In a machine of the character described, the combination of accumulating and printing mechanisms and actuating 120 means therefor; of a depressible key for disabling the accumulating mechanism, a latch for holding said key depressed, and a lock for preventing depression of such key during 125 operation of the accumulating mechanism by the actuating means, with provisions for holding said key depressed during an operation of the printing mechanism unaccompanied by an operation of the accumulating mechanism. 42. In a machine of the character described, the combination of accumulating and printing mechanisms and actuating 130 means therefor; of a depressible key for disabling the accumulating mechanism, a latch for holding said key depressed, and a lock for preventing depression of such key during operation of the accumulating mechanism by the actuating means, with provisions

for holding said key depressed during an operation of the printing mechanism.

40. In a machine of the character described, the combination with accumulating and printing mechanisms and actuating means therefor; of a depressible key for disabling the accumulating mechanism, and a reciprocating lock-plate adapted to engage said key when depressed and prevent it 10 from rising during an operation of the printing mechanism by the actuating means unaccompanied by an operation of the accumulating mechanism.

41. In a machine of the character described, the combination with accumulating and printing mechanisms and actuating means therefor; of a depressible key for disabling the accumulating mechanism, and a reciprocating lock-plate adapted to engage 20 said key to prevent its depression during

operation of the accumulating mechanism by the actuating means.

42. In a machine of the character described, the combination with accumulating and printing mechanisms and actuating means therefor; of a depressible key for disabling the accumulating mechanism, and a reciprocating lock-plate adapted to engage said key when depressed and prevent it from rising during an operation of the printing mechanism by the actuating means unaccompanied by an operation of the accumulating mechanism, said lock plate adapted to engage the key to prevent its depression during operation of the accumulating 30 mechanism. 35
